UNITED STATES PATENT OFFICE.

JOHN R. E. SUTHERN, OF MONCTON, NEW BRUNSWICK, CANADA.

ROTARY VALVE.

Application filed October 26, 1920. Serial No. 419,620.

To all whom it may concern:

Be it known that I, JOHN R. E. SUTHERN, a subject of the King of Great Britain, residing at city of Moncton, in the Province 5 of New Brunswick and Dominion of Canada, have invented certain new and useful Improvements in a Rotary Valve, of which the following is a specification.

This invention relates to rotary valves.

10 An object of this invention is to provide an improved rotary valve and to provide improved packing and lubricating means for said valve, and to provide an improved valve structure wherein, from a single casting 15 housing the inlet and exhaust chambers will open to a single port into the engine cylinder, and thereby aid in the co-operation and general efficiency of the operation of the piston of the cylinder without the escape- 20 ment of gases through an extra cylinder port.

A further object of this invention is to provide a means for breaking up and mixing the incoming combustion charge before 25 it enters the cylinder of the engine and in the valve, thereby promoting the efficiency of the engine and simplifying the carburetor construction.

A further object of this invention is to 30 provide a rotary valve structure in which the driving mechanism may be readily interchanged from end to end of the valve.

A further object of this invention is to provide against the fire igniting the fresh 35 fuel charge in the carburetor or inlet manifold, due to a blow-back from improper setting of the valves, or untimely sparking at plugs, or from other like reasons.

A further object of this invention is to 40 provide an improved inlet conduct into the valve and to provide improved packing means around the valve driving mechanism and to provide for an easy, quick and inexpensive method of keeping the valve driving 45 spindle in alignment.

A further object of this invention is to provide an improved means of keeping the valve properly seated.

With these and other objects in view, the 50 invention consists in the construction, the combination, the detail and the arrangement of parts as hereinafter more fully described and claimed.

In the drawings:

55 Figure 1 is an end elevation of my improved valve structure;

Figure 2 is a section at 2, 2 of Figure 1; Figure 3 is a section at 3, 3 of Figure 2; Figure 4 is a section at 4, 4 of Figure 2; Figure 5 is a view similar to Figure 1 with 60 the drive reversed; Figure 6 is a section at 6, 6 of Figure 5; Figure 7 is a section at 7, 7 of Figure 6, and

Figure 8 is a perspective of the main valve 65 member.

In the embodiment of my invention there is provided a valve of truncated cone shape 2, provided with a pair of ports 3 and 4, the port 3 leading downward in said valve 70 and the port 4 leading upward and being divided by a septum 5 of tortuous shape, which, at the periphery dividing the two ports 3 and 4 is substantially vertical, and which at the top of the port 3, and the bottom of the port 4 is substantially discal at its outer edge, thereby providing a relatively large chamber both above and below the partition with a limited valve space.

The valve 2 is provided at the top with an inwardly extending flange 6 and likewise at the bottom with an inwardly extending flange 7, the said flanges each being perforated with threaded holes 8, the said flanges being adapted to seat upon themselves respectively, perforated cap 14 and spider 16. Elbows 9 and 10 are retained to a valve housing 13 preferably formed integral with the engine cylinder, and being retained thereto by cap screws 11 passing through 80 flanges 12 on the said elbows.

Mounted on the top of the valve 2 is a perforated member 14, fitting upon the flange 6 and affixed thereto by cap screws 15. Affixed to the bottom of the said valve 2 in like manner is a spider 16, when it is desired to drive the valve from the bottom, but which is omitted in a top driving valve.

Beneath the perforated cap 14 is a screen 17, which screen is held between the cap 14 and the valve 2 upon the flange 6, and which is in the nature of wire gauze and is for the purpose of breaking up and mixing the incoming combustion charge before it enters the cylinder of the engine, and has a further purpose of preventing fire from igniting the fuel charge in the carburetor or in the inlet manifold which might be due from a blow-back from improper setting of the valves, or untimely sparking at plugs, or 95 from other like reasons.

Mounted centrally of the cap 14 and ex-

tending through the shell of the elbow 9, when there is a top drive, and extending into the inner wall of the elbow 9 when there is a bottom drive, is a spindle designated as 18 where it passes through the shell and as 19 where it extends only into the shell.

Surrounding the spindles 18 or 19 is a helical spring 20, which seats upon a shoulder 21 upon said spindles and which abuts at its upper end a washer 22, above which washer 22 is a set of balls adapted to roll between the washer 22 and a ball rest 23, the said ball rest 23 being on the lower part of the flanged portion of a ferrule 24 extending through a perforation 25 in the elbow 9 and being retained therein by a cap 30 provided with an intervening packing 31.

Mounted on the upper end of the spindle 18 is a beveled gear 32, held thereto by a pair of nuts 33 and 34 and a cotter pin 35. In the bottom drive the spindle 19 extends into a socket 26 and is likewise affixed to the cap 14. In the bottom drive the beveled gear 32 is affixed by the nuts 33 and 34 to a depending spindle 27 packed by the ferrule 23 and cap 25 to the lower elbow 10.

Surrounding the valve is preferably a water jacket 36. The ports 3 and 4 open into a cylinder port 38 extending at 39 partially around the cylinder wall.

Surrounding the said valve spiral, or cross, grooves 40 holding packing 41 to reduce to a minimum the possibility of leakage or pressure of gases between the walls of the taper bore and the rotating member contained within the bore. The spiral or cross grooving also serves the purpose of lubrication when lubricating oil is not inserted into or mixed with the fuel or combustible mixture forming the combustible charge of the engine.

In operation the incoming fuel passes through the elbow 9 and thence through the perforations in the cap 14 and into the upper chamber and out through the port 4 into the port 38 of the cylinder when the port 4 is in registration with the port 38. Upon a further rotation of the valve the port 3 comes in registration with the port 38 and the exhaust gases are let out through the port 3 and the lower chamber and through the exhaust elbow 10, the same being properly timed relative to the engine stroke by means interconnecting the beveled gear 32 with the crank shaft of the engine. This interconnection is accomplished in different types of engines (such as engines having a convenient means for attachment from the top, or such as engines having convenient means for attachment from the bottom of the valve) by merely interchanging certain parts of the structure herein set forth and with very slight new or added parts.

It will be noted further that the valve is disposed with its axis parallel to the piston of the engine, thereby providing a very easily lubricated and simply connected article and one which is run with a minimum of loss in mechanical efficiency.

Having thus fully described my invention, what I claim to be new is:

1. In combination with a rotary valve for internal combustion engines embodying a hollow valve sleeve having circular open ends and provided with a partition dividing the interior of the sleeve into non-communicating intake and exhaust chambers, the valve sleeve having parallel ports in the sides thereof respectively communicating with the intake and exhaust chambers, a wire gauze disk covering the intake chamber at one end of the valve sleeve, and a member detachably secured to said end of the valve sleeve and clamping the margin of the wire gauze disk against the adjacent end edge of the valve sleeve.

2. In an internal combustion engine, a power cylinder, a valve casing having open ends and provided with a port in the side thereof communicating with the cylinder, elbows secured to and communicating with opposite ends of the valve casing and adapted to respectively form intake and exhaust conduits, a hollow frusto-conical valve sleeve having circular open ends and formed with continuous bearing surfaces fitting the valve casing at opposite sides of the valve casing port, a partition dividing the interior of the sleeve into non-communicating intake and exhaust chambers, said valve sleeve having two parallel ports of the same size in the side thereof respectively communicating with the intake and exhaust chambers and arranged to successively register with the port in the valve casing, a perforated member rigid with the larger end of the valve sleeve, a shaft disposed coincident with the axis of the valve sleeve and having its inner end rigid with the perforated member, a bearing sleeve carried by the adjacent elbow and having said shaft journaled therein, an anti-friction thrust bearing for said shaft including an inner ball race and an outer ball race, the outer ball race constituting a flange on the inner end of said bearing sleeve, and a compression spring encircling said shaft between the inner ball race and the perforated member for seating the valve sleeve in the valve casing.

3. In an internal combustion engine, a power cylinder, a valve casing having open ends and provided with a port in the sides thereof communicating with the cylinder, elbows secured to and communicating with opposite ends of the valve casing and adapted to respectively form intake and exhaust conduits, a hollow frusto-conical valve sleeve having circular open ends and formed with

continuous bearing surfaces fitting the valve casing at opposite sides of the valve casing port, a partition dividing the interior of the sleeve into non-communicating intake and exhaust chambers, said valve sleeve having two parallel ports of the same size in the sides thereof respectively communicating with the intake and exhaust chambers and arranged to successively register with the port in the valve casing, a perforated member rigid with the larger end of the valve sleeve, a shaft disposed coincident with the axis of the valve sleeve and having its inner end rigidly and detachably secured to the perforated member, the outer portion of said shaft being journaled in the adjacent elbow, a compression spring encircling said shaft between the elbow and the perforated member for seating the valve sleeve in the valve casing, and means to facilitate attachment of a drive shaft to the smaller end of the valve sleeve.

4. In an internal combustion engine a power cylinder, a valve casing having open ends and provided with a port in the sides thereof communicating with the cylinder, elbows secured to and communicating with opposite ends of the valve casing and adapted to respectively form the intake and ex-

haust conduits, a hollow frusto-conical valve sleeve having circular open ends and formed with continuous bearing surfaces fitting the valve casing at opposite sides of the valve casing port, a partition dividing the interior of the sleeve into non-communicating intake and exhaust chambers, said valve sleeve having two parallel ports of the same size in the side thereof respectively communicating with the intake and exhaust chambers and arranged to successively register with the port in the valve casing, a perforated member rigid with the larger end of the valve sleeve, a shaft disposed coincident with the axis of the valve sleeve and having its inner end rigid with the perforated member, the outer portion of said shaft being journaled in the adjacent elbow, a compression spring encircling said shaft between the elbow and the perforated member for seating the valve sleeve in the valve casing, and a wire gauze disk covering the intake chamber at the larger end of the valve sleeve, said gauze disk having its margin clamped against the adjacent end edge of the valve sleeve by said perforated member.

In testimony whereof I affix my signature.

JOHN R. E. SUTHERN.
